SIGN.

E. GARET.

FURNITURE CASTER.

No. 18,266.

Patented Apr. 24, 1888.

UNITED STATES PATENT OFFICE.

EMILE GARET, OF HOBOKEN, NEW JERSEY, ASSIGNOR TO MERKLEN
BROTHERS, OF NEW YORK, N. Y.

DESIGN FOR A FURNITURE-CASTER.

SPECIFICATION forming part of Design No. 18,266, dated April 24, 1888.

Application filed March 19, 1888. Serial No. 267,792. Term of patent 14 years.

To all whom it may concern:

Be it known that I, EMILE GARET, of Hoboken, in the county of Hudson and State of New Jersey, have invented a new and original 5 Design for Furniture-Casters, of which the following is a specification.

The nature of my design is fully shown in the accompanying photograph, in which Figure 1 is a face view of my newly designed furniture caster, and Fig. 2 is a side view of the same.

Similar letters of reference indicate corresponding parts.

Heretofore many table legs have had their 15 sockets for receiving the balls used as casters made to represent a bird's talons or claws grasping the ball.

The leading feature of my design consists in a fanciful head of an animal or dragon and 20 teeth on the same embracing the ball.

A is the head of an animal, dragon, or other fantastic figure. B are the front teeth, slightly curved toward the back; C, the back teeth, slightly curved toward the front; D, a ball between the teeth; E, a socket on the top of the 25 head.

Having thus described my design, I claim as new and desire to secure by Letters Patent—

The design for a furniture-caster, the same 30 consisting of a head and teeth on the same and a ball between the teeth, substantially as shown and described.

In testimony that I claim the foregoing as my invention I have signed my name in presence of two subscribing witnesses.

EMILE GARET.

Witnesses:

OSCAR F. GUNZ,
SIDNEY MANN.
